UNITED STATES PATENT OFFICE

2,438,363

BUTTON BROACHING MACHINE

Jules Friedman, New York, N. Y.

Application October 27, 1943, Serial No. 507,821

4 Claims. (Cl. 79—1)

1

My present invention relates to button manufacturing apparatus, and more particularly to a button punching machine for forming mounting holes in the buttons.

In the manufacture of plastic buttons by molding, as well as in the manufacture of many other types of buttons, the mold or die which performs the final operation has prongs for forming the holes in the buttons. However, a thin film of plastic remains in each of the holes of the button, and it is necessary to clear this film. Heretofore, expensive and complex apparatus has been necessary in order to perform this operation. Attempts have been made to devise various types of mechanisms for automatically performing this operation without the necessity for manually treating each individual button.

An important characteristic of my invention is that a plurality of punching members is provided in a single unit for broaching the holes in the buttons as above set forth. These punching members have positive motion toward the button; and yet an important corollary characteristic of my invention is that the buttons are so arranged that they may yield to this positive movement of the punching members and move with the punching members.

The punching members may be positively and accurately driven without the necessity for complex spring arrangements in the punching members themselves.

When, however, the punching members come into contact with the button, the button is yieldingly mounted in such a manner that it may move with the punching member. This yielding mounting is obtained by holding the button in contact with the punching member by means of a spring biased flexible cover plate.

This spring bias permits the punching member to push the button up with it as the punching member rises; but as the punching member rotates while it rises, and the punching prongs on the punching member move into the holes in the button and against the films, the spring bias exerted when the buttons are raised is sufficient to break the film and force the button down onto the prong.

Thus, the operation previously thought necessary in the art is substantially reversed.

My invention differs from the prior art in that, in the first place, I do away with intermittent motion and the accompanying arms which must be adjusted within critical limits to index each button in the right place. The resulting motion is a smooth continuous one which does not re-

2

quire indexing of the buttons and does not jar the buttons out of the feed. The continuous motion permits greater output since the machine is not idle intermittently.

Instead of indexing each button and punching it, I provide a punch with each hole of the dial feed, and as the dial rotates, the punch rotates also so that the pins or prongs find their way into the holes of the button.

On further rotation of the plate, a cam or ramp makes the punches rise, and at this point a flexible cover plate is provided for the punches to push against and broach the button. In this way if anything is caught, or if a button has too thick a flash to push through, it simply raises the cover plate and the button passes through without the usual breakage which occurred in the old methods. As the dial goes further, a cam brings the punch down, and as it so does it there is a proper chute which disengages the button from the prongs of the punch and takes it from the machine.

My invention resides in the fact that I do away with all necessity for indexing and in that my buttons are punched from the underneath and are engaged by a continuous nonintermittent motion. The set of multiple punches makes this possible. I eliminate the necessity for accurate mechanism by employing the foregoing entirely different principles.

Previously, it was always thought necessary to positively drive the punching member up into engagement with the button and to positively remove the punching member from such engagement in order to complete the entire punching operation.

In my present invention, the punching member merely serves to push the button up against the bias of the spring, so that the spring itself will snap the button down onto the prongs of the punching member to broach the holes when the films at the end of the holes move into registry with the prongs.

Also, in my present invention, a longitudinal drive for moving the punch up and down is made possible which has no mechanical moving parts at all, that is, the end of the punch moves along an undulating rail which causes the punch to rise and fall as it moves.

Likewise, the drive for rotating the punch is, in my present invention, made a function of the rotary movement of the mounting means of my punch, so that a simple friction or gear connection is sufficient to rotate the punch.

Accordingly, a primary object of my invention

is the formation of an improved button broaching machine.

Another object of my invention is the formation of a button broaching machine having a longitudinally movable punching member wherein, however, an additional yielding means is provided for engaging the button holes with the punching member.

These and many other objects of my invention will become apparent in the following figures in which:

Figure 1 is a view in perspective of my novel button broaching machine.

Figure 2 is a top view of the button table of my button broaching machine.

Figure 3 is a cross-sectional view taken on line 3—3 of Figure 2 looking in the direction of the arrows.

Figure 4 is a schematic view of the mechanism illustrating its operation.

Figure 5 is a view in perspective of one of the punches.

Figure 6 is a cross-sectional view taken on line 6—6 of Figure 2 looking in the direction of the arrows.

Figure 7 is a cross-sectional view taken on line 7—7 of Figure 1 looking in the direction of the arrows.

Referring now to Figure 1, I have shown my improved button broaching machine which, for purposes of ease of operation and automatic loading and delivery, is mounted so that the entire mechanism is at an angle of the order of 45° from the vertical.

The mechanism, as a whole, consists of an upper button carrying plate 10, a pair of parallel punch carrying and positioning plates 11 and 12, and a bottom stationary guide plate 13.

As shown in Figures 1 and 3, the entire mechanism is mounted on a hollow pedestal 14 which is rigidly secured to (or may even be integral with) the underside of the bottom plate 13.

The bottom plate 13 and pedestal 14 are provided with a central opening 15, shown in Figure 3.

A shaft 16 is arranged within the hollow pedestal 14 co-axially therewith and extends up through the bottom stationary guide plate 13 to the punch-carrying plates 11 and 12 and the upper button plate 10. The drive shaft 16 is keyed to the plates 10, 11, and 12 so that these plates will rotate upon rotation of the drive shaft 16. Shaft 16 may, in one form of construction, be keyed to the spacer plate 17 between plates 10 and 11. Plates 10 and 11 are secured to the spacer plate 17 by means of bolts 18. Plates 11 and 12 may be interconnected by the bolts 19 and spaced properly by the bushings 19a.

Shaft 16 is operated for rotary motion in a counterclockwise direction with respect to the top view of Figure 2 by any suitable driving means including a motor and connecting elements between the motor and the shaft 16. The rotation of shaft 16 thus results in a corresponding rotation of the plates 10, 11, and 12 with respect to the plate 13.

Plate 10 is provided with a plurality of recesses 20 for positioning buttons. These recesses 20, as shown in Figures 3 and 6, are counterbored in such a manner as to provide an opening 21 in the underside through which the punching prongs hereinafter described may pass, an annular ledge 22 on which the button may be seated, and an annular flaring portion 23 connecting with the upper surface of the plate 10 to provide a wider

opening and thus permit the button to slide down onto the ledge 22. In appropriate cases, the top plate 10 may be provided with a plurality of simple openings; and a set of different plates or rings each having different size ledges 22 may be provided to be secured on the plate 10 so that the same machine may readily be used for different size buttons. Where necessary, however, plates 10 may be readily interchanged for different size buttons by removing bolts 18, changing the plate, and reinserting the bolts 18.

Each of the plates 11 and 12 is provided with a plurality of openings 25 and 26 respectively adjacent the periphery for positioning the punch members 30 in a vertical position beneath each of the button recesses 20 in the upper plate.

Consequently, each of the openings 20 in the upper plate 10 has in vertical alignment immediately beneath it an opening 25 in the plate 11 and an opening 26 in the plate 12. Since the plates 10, 11, and 12 are all keyed to the shaft 16 and rotate simultaneously, this alignment of the respective sets of openings 20, 25, and 26 is not disturbed at any time during the operation of the mechanism.

Therefore, any punch 30 which is arranged in any vertically aligned pair of openings 25 and 26 will likewise be in alignment with the center of an opening 20 and will always remain in alignment therewith.

The pedestal 14 of the entire mechanism is so mounted that the machine as a whole, or at least all of the parts shown thereof in Figures 1 and 8, is tilted at a substantial angle to the vertical. This angle may be of the order of 45°—although a wide variation in the angle of tilt may be made without interfering substantially with the operation of the mechanism.

The mechanism, as a whole, is provided with a hopper 31 which is stationarily supported so that it does not rotate with the plates 10, 11, and 12. Accordingly, this hopper is positioned in any suitable manner by brackets 31a which are secured to a portion of the periphery of the stationary guide plate 13.

The hopper is arranged so that its closed side is at the lower end of the tilted mechanism. Buttons may thus be thrown into the top of the hopper and will be retained in position by the closed end of the hopper.

As will be seen from the drawings, the hopper 31 follows and is in close alignment with the series of peripheral openings 20 for receiving the buttons. To ensure that the inner surface of the hopper follows the line of recesses accurately, an inner guide plate 32 may be provided on the hopper in close proximity to the top surface of plate 10 and adjacent to the line of recesses 20.

As the plate 10 rotates with respect to the hopper, the buttons are agitated and move about, and, owing to the flaring portion 23 of the recess 20, buttons will set themselves in the recesses 20 as these recesses move beneath the pile of buttons in the hopper. This is further ensured, as above pointed out, by reason of the fact that the hopper is closely adjacent to the peripheral line of button receiving recesses, so that the buttons at the bottom of the pile and against the hopper wall are in a position to fall into any open recess.

After a button has entered one of the recesses 20, as the recess passes through the hopper 31, the button is carried around by the plate 10 until the button passes beneath the arcuate flexible spring biased plate 35.

Plate 35 is stationarily mounted so that it does not move with the plate 10. However, the plate 35 is so mounted that it is biased toward engagement with the surface of the plate 10 and specifically with that portion of the surface which contains the recesses 20.

The plate 35 is also so mounted that it may be moved away from the plate 10 but, on relaxation of the force tending to move the plate 35 away from the plate 10, plate 35 will snap back to the plate 10.

The plate 35 is thus mounted and accurately positioned with respect to the series of peripheral openings 20 by means of a transverse positioning member 40 which is held in position in any suitable manner by the vertical posts 43 and 44.

The posts 43 and 44 are mounted on brackets 45 and 46 which are secured in any suitable manner to the underside of the stationary guide plate 13.

One method of securing the transverse plate 40 in appropriate position on the posts 43 and 44 is passing bolts 50 and 51 through appropriate openings in the upper transverse positioning member 40, and the placing of longer sleeves 55 and 56 over the respective bolts 50 and 51 so that these sleeves rest on the upper sides of the respective brackets 45 and 46, passing the threaded ends of the bolts 50 and 51 through appropriate openings in the ends of the brackets 45 and 46, and applying a securing nut 60 to the end of each bolt. By this means, the transverse positioning member 40 is securely held in appropriate predetermined relation.

The arcuate flexible metal plate 35 is biased into position by the spring biased rods 62, 63, and 64 which bear against the upper surface of plate 35.

The three rods 62, 63, and 64 pass through appropriate openings in the upper transverse plate 40. A compression spring 66 is secured around each rod; the bottom end of each spring bearing against the ledge or abutment 65 on each rod.

At their upper ends, each spring 66 bears against the underside of the positioning member 40, and thus the spring is compressed driving the rods 62, 63, 64 downwardly.

The upper surface of flexible plate 35 is provided with three bushings 68, 69, 70 secured thereto in any suitable manner, as by brazing, to receive the ends of rods 62, 63, and 64.

Thus, the spring pressed rods 62, 63, 64 press the flexible plate 35 down on the moving plate 10, and the engagement of the rods in the bushings maintains plate 35 in position. Since plate 35 is flexible, the buttons raising under it, in the manner hereinafter described, may raise different portions of plate 35 to compress different springs 66; and, even though a number of buttons are simultaneously under the plate 35, they are all simultaneously subject to downward spring pressure. Plate 35 may be extended somewhat in a clockwise direction to enable the buttons to enter freely beneath it; and to further ensure that the buttons may enter beneath plate 35, the end 36 of plate 35 may be bent upwardly.

The essential portion of the button broaching mechanism comprises the punch 30, which is illustrated individually in Figure 5, and the operation of which is shown in Figures 1, 3 and 6.

The punch 30 is a single integrated member comprising a main vertical section 90, a lower rounded stud 91 of hardened steel, and upper prongs 92. A constricted section 93 is also pro-

vided for purposes hereinafter described. Prongs 92 are a force fit in appropriate holes in the end of punch 30 so that they may readily be replaced should breakage occur.

5 The prongs 92 are intended actually to broach the film in the button holes of the buttons mounted in the recess 20 of the plate 10.

The main vertical section 90 is provided with a knurled portion 94.

10 As is seen in Figures 1, 3, and 6, the punch 30 is so mounted in the unit as a whole that each punch passes through a pair of vertically aligned openings 25 and 26 in the positioning plates 11 and 12, and so that the hardened steel stud 91 bears against the upper surface of the stationary guide plate 13, and so that the prongs 92 are in registry with the button recesses 20 which are in vertical alignment with the openings 25 and 26 through which the punch passes.

20 The knurled section 94 is thus, as shown in Figures 1, 3, and 6, positioned between the plates 11 and 12.

A curved frictional surface member 100 is supported in any suitable manner as, for instance, by the screws 101 and the bracket 102, on the stationary guide plate 13.

The bracket 102 is so arranged that the member 100 registers with the space between the positioning plates 11 and 12.

30 The friction surfaced member 100 is adjustably positioned by means of the screws 101 and may be secured in any selected position.

In addition, the bracket 102 may be made of very heavy spring steel to hold the member 100 in the selected position; but the spring steel of the bracket 102 is just sufficiently flexible to permit the rack to be displaced somewhat outwardly should a slight deviation in exact registry between the member 100 and punch members 30 occur.

40 As the punch members 30 are carried about by the plates 11 and 12 in which they are positioned, the hardened steel stud 91 slides along the stationary guide plate 13.

45 When the respective punch members successively move into position with respect to the member 100, then the knurled section 94 on the punch member engages the friction member 100, and the punch is thereby rapidly rotated. When 50 the punch moves out of registry with the member 100, then this rotating motion ceases.

55 The member 100 is arranged so that it substantially underlies and is co-terminous with the spring biased arcuate plate 35, so that the punch is rotated as it passes beneath this spring plate. Member 100, as seen in Figure 3, may project for a substantial distance to a point well beyond that where the buttons are punched so that the punches may begin their rotation and so that the 60 prongs may move into registry with the buttons at some distance before the punches rise.

65 As seen in Figure 6, member 100 is preferably provided with a rubber surface to engage the punches 30 and cause them to rotate. The end of member 100 which is first met by the punches 30 may be curved outwardly to a slight extent to ensure that the punches may enter into engagement with the rubber surface of member 100.

70 The stationary guide member 13 is provided with a ramp 110, see particularly Figure 4, which underlies the portion of the mechanism over which the member 100 and plate 35 are positioned.

75 Thus, as the punch 30 is moved along the guide

plate 13 between plates 14 and 12, and as this punch moves along with the button carrying plate 10 and the button positioned in the recess 20 immediately above the punch—then, when the punch moves into position beneath the spring plate 35 and against the member 100 so that it is rotated, the lower hardened steel stud 91 of the punch rides up the inclined section 112 of the ramp onto the substantially horizontal section 113 thereof.

The punch, which is now rotating, is thus, by means of the ramp 110, pushed up so that the prongs 92 rise up in the button carrying recess 20. The prongs 92 thus push the button which is in the recess up against the spring pressed plate 35 and tightly press the button against this plate. The button then pushes a portion of the flexible plate 35 up against the bias of the springs 66.

When, during the rotation of the punch 30, the prongs 92 move into registry with the holes in the button, they enter the holes and bear against the films in the holes. The springs 66 are compressed and have sufficient force to break these films and to snap the button down onto the prongs 92.

For this purpose, it will be obvious that the plate 35 is flexible and may undulate so that each button is subjected to pressure.

It will also be obvious that where the flash film is too thick, the force is a yielding one so that even though the film is not broken, the button plate keeps on moving and no jamming or breakage occurs.

As will thus be seen, the buttons which are thus mounted in the respective recesses 20 have their films broached as the punch passes beneath the spring pressed plate 35.

Once the buttons have thus been broached, the punch may be withdrawn therefrom, by reason of the fact that the lower end of the punch 91 rides down from the ramp 110 while the next button and punching member moves into position.

The buttons are brought around to the delivery end of the machine where they must now be removed. Removal is accomplished by automatically raising the buttons above the level of the uppermost plate 10 so that they may be lifted off. This is performed by having the punch 30 ride up the incline of an additional ramp 120.

The ramp 120 is much higher than the original ramp 110. The punches are not rotated as they ride up on this ramp, but the punching members 92 engage with the button to lift it substantially clear of the upper surface of the plate 10.

An exit chute 122 is provided for the buttons so that the buttons may ride up thereon at this point. For this purpose, the exit chute ends in a pair of tines 123 which are arranged in the path of the moving buttons with the ends of the tines substantially at the point where the buttons are raised to their highest level above the table by the ramp 120.

The ends of the punching members 92 on the punch pass between the tines 123, while the button itself rides up on the surfaces of the tines, since the free ends of the tines are substantially in engagement with the surface of the button carrying plate 10.

After the button is thus engaged on the tines 123, then, as the punch moves along with the plate, the button is pulled upward on the inclined tines 123 and peeled off of the punch, and falls down chute 122.

A side plate 125 adjacent ramp 120 has a re-entrant flange 126 which engages between stud 91 and the body 90 of the punch 30 to pull the punch down as it travels off ramp 120. That is, flange 126 is inclined to the plate 13 to accomplish this function so that the punches may be below the level of the recesses 20 when buttons fall therein.

Thus, as will now be obvious to those skilled in the art, the essential operations of my device are performed without the utilization of oscillatory members which must be positively driven. Instead of a positive drive engagement for the punches which must move them up, and which driving engagement must then be reversed to pull them down again, the punches are moved up and down by simple undulating ramps.

The rotation of the punches at the appropriate time is accomplished by a simple frictional engagement of the punches with a stationary member section adjacent to a portion of the path of the punches.

It will be obvious, of course, that even a gear and rack engagement may be sufficient to accomplish this purpose, although the frictional arrangement does not interfere in any way at all with the vertical sliding motion.

The buttons are punched upwardly from the bottom and by a continuous motion so that the film is broached cleanly and without chipping the button.

In addition, also, although the punch member 30 may be operative by itself to effect the punching operation, in the last analysis, my present invention is so arranged that the punching operation occurs by reason of the compression of spring 66, that is, when the punch is raised and while it rotates, it simply raises the button up. Thus the punching operation is a yielding one and if any button should fail to be punched, the machine is not jammed.

By this means, even the punching operation is done by means of a yielding member which may readily accommodate itself to variations in the button structure or variations in the strength of the film.

The punches may simply be lifted out and different punches reinserted to punch buttons having different spacings between holes; or the ends of the punches carrying the prongs may have removable tips in threaded engagement with the body of the punch.

The operation of all of the foregoing elements of my invention have been described in connection with specific descriptions of the various parts thereof.

Many variations and modifications of my invention should now be obvious to those skilled in the art. Accordingly, I prefer to be bound not by the specific disclosures herein but only by the appended claims.

I claim:

1. In a button broaching machine; a continuously rotatable member having a plurality of recesses for receiving and positioning buttons having holes to be broached; each of said recesses having an opening registering with the section of the button having said holes; a punch individual to each recess and having prongs introducible into the opening of said recess; and means for mounting each of said punches in a position normal to the plane of the recess with which it cooperates; said punch mounting means being connected to the said continuously rotatable member and movable therewith; each punch

being at all times in registry with its recess; and a stationary guide plate mounted beneath said continuously rotatable member and said punch mounting means; the lower end of each punch moving along the surface of said guide plate; said guide plate having a ramp in the path of movement of said punches; the punches successively rising as their lower ends move onto the ramp; the opposite ends of the punches carrying the prongs moving into engagement with the button positioned with respect thereto; a stationary curved friction surfaced member disposed above the plane of said stationary guide plate and substantially in alignment with said ramp; said last mentioned member extending along the path of movement of said punches; a friction surface on said punches registerable with said friction surfaces member; said punches moving successively into engagement with said friction surfaced member and being rotated by their movement with respect thereto, as they are raised, to cause said prongs to register with said holes to be broached; and means cooperating with each punch as it is raised to effect the broaching of the button.

2. In a button broaching machine; a continuously rotatable member having a plurality of recesses for receiving and positioning buttons having holes to be broached; each of said recesses having an opening registering with the section of the button having said holes; a punch individual to each recess and having prongs introducible into the opening of said recess; and means for mounting each of said punches in a position normal to the plane of the recess with which it cooperates; said punch mounting means being connected to the said continuously rotatable member and movable therewith; each punch being at all times in registry with its recess; and a stationary guide plate mounted beneath said continuously rotatable member and said punch mounting means; the lower end of each punch moving along the surface of said guide plate; said guide plate having a ramp in the path of movement of said punches; the punches successively rising as their lower ends move onto the ramp; the opposite ends of the punches carrying the prongs moving into engagement with the button positioned with respect thereto; a stationary curved member disposed above the plane of said stationary guide plate and substantially in alignment with said ramp; said last mentioned member extending along the path of movement of said punches; a portion of each punch being engageable with said member; said punches moving successively into engagement with said surfaced member and being rotated by their movement with respect thereto, as they are raised, to cause said prongs to register with said holes to be broached; and means cooperating with each punch as it is raised to effect the broaching of the button.

3. In a button broaching machine; a continuously rotatable member having a plurality of recesses for receiving and positioning buttons having holes to be broached; each of said recesses having an opening registering with the section of the button having said holes; a punch individual to each recess and having prongs introducible into the opening of said recess; and means for mounting each of said punches in a position normal to the plane of the recess with which it cooperates; said punch mounting means comprising a member connected to the said continuously rotatable member and movable therewith and another member supporting and guiding the base of each punch; each punch being at all times in registry with its recess; said punches being readily manually removable by lifting the same up and out through the opening in the recess with which it registers.

4. In a button broaching machine; a continuously rotatable substantially circular member having a plurality of recesses for receiving and positioning buttons having holes to be broached; each of said recesses having an opening registering with the section of the button having said holes; a punch individual to each recess and having prongs introducible into the opening of said recess; and means for mounting each of said punches in a position normal to the plane of the recess with which it cooperates; said punch mounting means being connected to the said continuously rotatable member and movable therewith; each punch being at all times in registry with its recess; means for successively raising each of said punches into engagement with the button positioned with respect thereto; a stationary spring biased resilient member engaging the surface of said continuously rotatable member over the said recesses and along a substantial arc of said continuously rotatable member; and means for rotating said punches on their individual axes as they move along said arc beneath said resilient member to cause the prongs thereof to register with the holes in said buttons; and means for raising said punches during their traverse beneath said resilient member; said punches when raised cooperating with said resilient member to broach said buttons.
